UNITED STATES PATENT OFFICE.

PHILIP T. DODGE, OF NEW YORK, N. Y., ASSIGNOR TO MERGENTHALER LINOTYPE COMPANY, A CORPORATION OF NEW YORK.

TYPOGRAPHICAL MACHIN

1 120 261

Specification of Letters Patent.

Patented Mar. 2, 1915.

Application filed May 28, 1914. Serial No. 841,417.

To all whom it may concern:

Be it known that I, PHILIP T. Dodge, a citizen of the United States, residing at New York, in the county of New York and State of New York, have invented certain new and useful Improvements in Typographical Machines, of which the following is a specification, reference being had therein to the accompanying drawing.

My invention relates to typographical machines, such as linotype machines of the general organization represented in Letters Patent of the United States, No. 436,532, to O. Mergenthaler, wherein circulating matrices are released by suitable escapements from a magazine in the order in which their characters are to appear in print and then assembled in line, the composed line transferred to the face of a mold, the mold filled 20 with molten metal to form a slug or linotype against the matrices which produce the type characters thereon, and the matrices thereafter returned through distributing mechanism to the magazine from which they 25 started.

More particularly, it relates to the use of a number of fonts or sets of matrices representing different sizes or styles of type, in such manner that any font may be brought 30 into action at will; and to this end is employed a series of magazines in combination with means for shifting them and for bringing any selected one into operative position.

One of the principal advantages derived 35 from my improvements is the ability to employ a single series of escapements in connection with the plurality of movable magazines, the parts being arranged so that the escapements may be connected to one or 40 another of the magazines at will.

The specific construction of the parts will be described in the specification and the invention finally pointed out in the claims.

In the accompanying drawings, I have 45 shown my invention in preferred form and by way of example, and as applied to the commercial "Model K" linotype machine, or as disclosed in Letters Patent of D. S. Kennedy, No. 1,104,512, dated July 21st, 1914; 50 but obviously many changes and variations may be made therein, and in its mode of application, which will still be comprised within its spirit. Thus, it may be applied to other forms of typographical machines, not 55 only line casting machines which handle

matrices, but also typesetting machines, typecasting machines, etc., which handle type or dies.

Generally speaking, I desire it to be understood that I do not limit myself to any 60 specific form or embodiment, except in so far as such limitations are specified in the claims.

Referring to the drawings: Figure 1 is a side elevation of the upper portion of the machine, with my improvements embodied therein; Fig. 2 is a similar view showing the parts in different position; Fig. 3 is a section on the line 3—3 of Fig. 2; Fig. 4 is a vertical section through the lower part of the magazines, etc.; Fig. 5 is an elevation, partly broken away, illustrating the removal of a magazine; Fig. 6 is a detail section on the line 6—6 of Fig. 5; and Fig. 7 is a side elevation of a modified form.

The matrices X are stored according to font in the magazines A and B, which may be shifted so as to bring either into operative relation to the face plate C, distributing devices D, and channel entrance D¹. In the 80 preferred form illustrated, only two such magazines are disclosed, but obviously the number thereof may be increased if desired, as the principles of construction and operation apply similarly to a greater number. The magazines A and B are mounted upon the customary base frames A¹ and B¹ respectively, which in turn are connected to the supporting frame E, and with reference to which they may be shifted to bring 85 the selected magazine into action, the frame E resting upon and being in turn sustained by the framework of the machine. The magazine B rests upon the sustaining or base frame B¹ in the usual manner, and the 90 upper base frame A¹ lies upon the magazine B, it being pivotally connected near its upper end, and at opposite sides thereof, to upward extensions or guides from the frame B¹, in such manner that it may be readily 95 disengaged therefrom when desired. The magazine A rests upon and is carried by the base frame A¹.

In order to effect the vertical shifting of the magazines with reference to the supporting frame E, the frame is provided with means comprising the cams G upon the transverse rock shaft G¹, near the forward end of the frame, and adapted to engage the rollers B²⁰ on the frame B¹, and two pairs 105

- 2
- of toggle links H and H¹, near the end of the frame, the upper links H being connected at one end to the base frame B¹, and the lower links H¹ at one end to the frame E. These cams and toggle devices are suitably connected, and the shaft G¹ is provided with a handle J, the operation of which effects the elevation of the base frame B¹ and the several parts supported thereby.
- 5 The feature so far described, in construction and mode of operation, and except as hereinafter indicated, are substantially the same as those in the Kennedy patent already referred to, wherein they are designated by 10 substantially the same letters of reference.
- 10 In the Kennedy patent each of the magazines is equipped with its own series of escapements, which is shifted into and out of operative relation to the escapement actuating devices, as the respective magazines are brought into action. In the present instance, I employ a single bank of escapements F, which are mounted permanently on the machine frame and so located as to 15 coöperate with the selected magazines, as they are successively moved into operative position. In order to hold the matrices in the magazine during shifting, each of them is provided with the locking rock shaft K, 20 or equivalent means, which may be operated in any desired manner, as will be familiar to those skilled in the art. The escapements F are preferably of the ordinary construction, comprising (Fig. 4) the ordinary centrally pivoted lever, and the pawls F¹ and F² adapted to be projected alternately into the magazine channel by suitable actuating 25 means, such for instance as the spring F³ and reed F⁴. Each of the magazines is 30 formed with openings in its under face to receive the escapement pawls.
- The arrangement whereby the several magazines are brought into engagement with the single bank of escapements will 35 next be described. It will be observed that the upper magazine A projects forwardly and beyond the magazine B, and overhangs it to a considerable extent, so that the same movement that shifts it into coöperation 40 with the assembling and distributing devices, also brings it into operative relation to the bank of escapements F. In other words, the manipulation of the arm J alone is sufficient either to elevate it to inactive 45 position, as shown in Fig. 2, or to lower it to active position, as shown in Fig. 1, at which latter time it is brought automatically into engagement with the stationary 50 bank of escapements F.
- 55 The mode of bringing the lower magazine B into action and into operative relation to the escapements is somewhat different, and involves not only its vertical shifting, but also its relative longitudinal movement with 60 relation to the magazine A and the frame B². By the manipulation of the handle J, and through the instrumentality of the cams G and toggle members H, H¹, the magazines are first elevated to the position indicated in Fig. 2. The magazine B is next moved 70 forwardly, as indicated by dotted lines, and is then lowered slightly, as shown in Fig. 4, to bring its forward end into engagement with the escapements. When it is desired to shift the magazine B out of action, the reverse operation is performed, namely, the magazine is slightly raised to free it from the escapements, and it is then moved rearwardly to its original position.
- 75 In order to secure the slight difference in 80 level, necessary to engage and disengage the magazine B and the escapements, the cams G (Figs. 1 and 4) are formed with two depressions G¹⁰ and G²⁰ at different radial distances from their centers, as distinguished 85 from the cams in the Kennedy application, which are formed with only one depression. When the roller B²⁰ engages the depressions G¹⁰, the magazine is in the elevated position indicated in Fig. 2. After the magazine 90 moves forward, the cam G is turned until the roller enters the depression G²⁰ (see Fig. 4), whereby the magazine is caused to descend into engagement with the escapements F.
- 95 The means for holding the magazine B in its forward and rearward positions respectively comprise the customary transverse bar B⁵ on the bottom of the magazine, which in its forward position engages with the lip 100 B⁶ at the front end of the frame B¹, and in its rearward position with the movable latches L. These latches are mounted upon the transverse shaft L¹ journaled in the base frame B¹, and provided at one end with the 105 finger piece or handle M, whereby the latches may be swung out of active position, in order to permit the forward and downward movement of the magazine to the position indicated by dotted lines in Fig. 2, 110 wherein it is arrested by the engagement of the bar B⁵ with the lip B⁶, as best shown in Fig. 4. A spring L² connected to the shaft L¹ (Fig. 3) tends normally to restore the latches L to their normal arresting position, 115 and a spring-actuated detent M¹ (Fig. 6), mounted in the base frame B¹ and adapted to engage the finger piece M, serves to hold them there. As previously described, the base frame A¹ rests directly upon the magazine B, and in order to permit the easy forward and backward movement of the latter, the frame is provided with anti-friction rolls A⁵ which rest upon the magazine.
- 120 As so far described, the forward and backward movement of the magazine B is effected by its direct manual shifting and in the manner indicated. However, in Fig. 7, I have shown a modified form dispensing with the latches L and their connected parts,

and wherein is provided a cam P mounted on a short stud P² carried by an upstanding lug on the base frame B¹ and having an operating handle P¹, the cam P engaging with a stud or roller P³ upon the side of the magazine B, so that the operation of the handle P¹, through the engagement of the cam with the roller, either permits the magazine to slide forwardly or restores it to retracted 10 position according to the direction in which the handle is moved.

My improvements also permit the ready removal and replacement of the magazines. For instance, when the parts are in the position shown in Fig. 2, the upper magazine A may be readily disengaged from its base frame A¹ and allowed to slide forwardly out of the machine. If it be desired to remove the lower magazine B, the frame E is moved 20 upwardly to the position shown in Fig. 5, wherein it is supported and secured by the pivoted arm or prop O, as set forth in the said Kennedy application; and the base frame A¹ is then lifted out of contact with the magazine B, to permit the unimpeded movement of the latter. In order to hold the base frame A¹ in its elevated position, I provide it at opposite sides with gravitating arms or catches N, adapted to engage with 25 studs upon the lower base frame B¹, these arms being of sufficient length to hold the frame A¹ out of contact with the magazine B and permit its free removal.

As previously stated, I have shown my 35 improvements only in preferred form and by way of example, and as adapted to a linotype machine, but obviously many modifications and alterations therein, and in their mode of adaptation, will suggest themselves to those skilled in the art, without departure from the scope of the invention.

Having thus described my invention, its construction and mode of operation, what I claim and desire to secure by Letters Patent 45 of the United States, is as follows:

1. In a typographical machine, the combination of a plurality of magazines, and a single series of escapements adapted to engage within the magazines, the said magazines 50 being movably arranged so that one or another may be brought into operative relation to the escapements.

2. In a typographical machine, the combination of a plurality of magazines, and a single series of escapements therefor, the said magazines being each provided with 55 openings in its face to receive the escapements and movably arranged so that the escapements may be engaged in the openings 60 in one or another thereof.

3. In a typographical machine, the combination of a magazine and its sustaining frame, with a series of escapements mounted independently of the frame, the said magazine 65 being provided with openings in its

face to receive the escapements and movable relatively to its frame into and out of operative relation to the escapements.

4. In a typographical machine, the combination of a plurality of magazines movable as a whole to bring one or another into use, and a stationary series of escapements, the said magazines being each provided with openings in its face to receive the escapements and arranged so as to be movable, 70 one independently of another, into and out of operative relation to the escapements. 75

5. In a typographical machine, the combination of a stationary series of escapements, a plurality of magazines each provided with 80 openings in its face to receive the escapements, a movable frame wherein the magazines are mounted, the said magazines being movable, one independently of another, relatively to the frame into and out of operative 85 relation to the escapements.

6. In a typographical machine, the combination of a stationary series of escapements, and a plurality of magazines each provided with openings in its face to receive the escapements and movable as a 90 whole and also relatively to each other to bring a selected one into operative relation to the escapements.

7. In a typographical machine, the combination of a stationary series of escapements, a magazine provided with openings in its face to receive the escapements, a sustaining frame therefor, and means for holding the magazine in different longitudinal 95 positions on the frame, one in operative relation to the escapements and another out of operative relation thereto. 100

8. In a typographical machine, the combination of a stationary series of escapements, a magazine in the rear of the escapements and provided with openings in its face to receive them, and a frame to shift the magazine above or below the level of the escapements, the said magazine being movable forwardly and backwardly on the frame into and out of operative relation to the escapements. 105

9. In a typographical machine, the combination of a stationary series of escapements, a plurality of magazines each provided with openings in its face to receive the escapements, and a movable frame therefor, the said magazines being arranged in said frame so that one may be moved thereby directly into and out of operative relation to the escapements. 115 120

10. In a typographical machine, the combination of a stationary series of escapements, a plurality of magazines, and a movable frame therefor, the magazines being arranged in overlapping relation in said frame, so that a forward magazine may be moved thereby directly into and out of operative 125 relation to the escapements, and a 130

4
rear magazine being slidably arranged in said frame so as to be movable forward and backward into and out of operative relation to the escapements.

5. 11. In a typographical machine, the combination of fixed assembling devices, a plurality of magazines, and a movable frame therefor, one of said magazines being arranged in the frame so as to be moved 10 thereby directly into and out of operative relation to the assembling devices, and another of the magazines being located in the rear of the assembling devices and slidably arranged in the frame so as to be movable 15 into and out of operative relation to the assembling devices.

12. In a typographical machine, the combination of a stationary series of escapements, and a magazine provided with openings in its face to receive the escapements 20 and movable both vertically and endwise to locate it in operative relation to the escapements.

13. In a typographical machine, the combination of a stationary series of escapements, and a plurality of magazines, one of said magazines being arranged to move vertically directly into operative relation to the escapements, and another of the magazines 30 being arranged to move both vertically and endwise into operative relation to the escapements.

14. In a typographical machine, the combination of assembling devices, and a plurality of magazines, one of said magazines 35

being arranged to move vertically directly into and out of operative relation to the assembling devices, and another of the magazines being arranged to move both vertically and endwise into and out of operative 40 relation to the assembling devices.

15. In a typographical machine, the combination of a stationary series of escapements, a magazine, its sustaining frame, and means mounted independently of the magazine for shifting the magazine longitudinally relatively to the frame into and out of operative 45 relation to the escapements.

16. In a typographical machine, the combination of a stationary series of escapements, a plurality of magazines each provided with openings in its face to receive the escapements, and means for shifting the magazines, one independently of another, 50 into and out of operative relation to the 55 escapements.

17. In a typographical machine, the combination of a stationary series of escapements, and a plurality of magazines each provided with openings in its face to receive the escapements and one movable independently of another into and out of operative 60 relation to the escapements.

In testimony whereof, I have affixed my signature in presence of two witnesses.

PHILIP T. DODGE.
